UNITED STATES PATENT OFFICE.

WILLIAM HENRY LINDENFIELD, OF LEXINGTON, TENNESSEE.

OIL-CUP.

1,397,838.

Specification of Letters Patent.

Patented Nov. 22, 1921.

Application filed September 30, 1920. Serial No. 413,773.

To all whom it may concern:

Be it known that I, WILLIAM HENRY LINDENFIELD, a citizen of the United States, and a resident of Lexington, in the county 5 of Henderson and State of Tennessee, have invented certain new and useful Improvements in Oil-Cups, of which the following is a specification.

My invention is an improvement in oil 10 cups, and has for its object to provide mechanism in connection with oil cups of the Hancock inspirator type for preventing accidental displacement of cover and feed valve, due to jars from the machinery upon 15 which the cup is used.

A further object of the invention is to provide mechanism in connection with the valve stem, for locking said stem to permit the feed to be regulated.

20 In the drawings:

Figure 1 is a side view of the improved cup,

Fig. 2 is a vertical section,

Fig. 3 is a top plan view of the cup,

25 Fig. 4 is a bottom plan view of the cover,

Fig. 4^a is a detail section showing the feed stem,

Fig. 5 is a top plan view of another 30 form of cup,

Fig. 6 is a top plan view of the cover,

Fig. 7 is a bottom plan view of the cover,

Fig. 8 is a side view of the valve stem of 35 the embodiment shown in Figs. 5 to 7, the top being in section,

Fig. 9 is a top plan view of the top.

In the embodiment of the invention shown in Figs. 1 to 4, the cup comprises a body 1 which has an externally threaded nipple 2 at its lower end for engaging an opening in 40 the machinery to be lubricated, which is indicated at 3, and the body has a marginal rib 4 at its lower end of polygonal outline for engagement by a wrench or the like to place the cup.

45 The nipple 2 has an axial opening 5, which is reamed or flared at its upper end, as indicated at 6, the flaring portion of the bore being in an inward extension of the 50 nipple, the said nipple being extended above the bottom of the cup body. This flaring portion 6 is a valve seat with which co-operates with the tapered portion of a needle valve 7, the said valve having threaded engagement with a nut 8 supported by the 55 top 14 of the cup. This needle valve has a

cup shaped extension 9 at its top, and the extension has a pair of oppositely extending ears 10, the body of the cup-shaped extension being coaxial with the valve. 60

The cover of the oil cup consists of a central portion 11 and radial extensions 12, the said extensions extending in opposite directions and being designed to cover arc shaped openings 13 in the top 14 of the cup. 65 These openings are oppositely arranged and the extensions 12 are, as before stated, shaped to cover and close the openings.

The cover 11 has a central nipple 15 extending on both sides of the cover, and the 70 nipple is of greater diameter than the threaded portion of the valve 7 which it encircles, an inwardly extending rib 16 being provided for engaging the valve to center the same. A coil spring 17 is arranged between the cupshaped extension 9 of the valve stem and the rib 16, and this spring acts normally to press the valve upwardly. The cup shaped extension 9 has ears 10 for convenience in turning the same and by 80 turning the valve, it will be evident that the extent of the opening through the passage 5 may be varied.

In order to prevent accidental displacement of the cover 11, I provide in the under face of the cover at points directly opposite to each other rounded lugs 18 in the form of balls which are embedded and held in openings in the cover 11, and these balls are adapted to engage recesses 19 in the 90 central portion of the top of the cup. The action of the spring 17 normally holds the balls in engagement with the recesses 19, but by lifting up on the cover or by merely turning the cover the balls may be released 95 thus acting to turn or force the cover outwardly toward the extension. The cover is also provided on one of the extensions 12 with a depending lug 20, and this lug is adapted to engage a notch or recess 21 in 100 the top of the oil cup when the balls 18 are in engagement with the recess 19.

In Figs. 2 and 4^a, there is shown mechanism for preventing accidental displacement of the feed stem, and to lock said 105 stem in adjusted position. This mechanism comprises a slot 7^a in the needle valve stem, the slot extending from about the lower end of the extension 9 to below the threaded portion of the stem, and above the rib 16 before 110 mentioned.

Locking pins 8^a and 8^b are arranged in

this slot, the pin 8^a being below the rib 16, while the pin 8^b is above the said rib. The pin 8^a is adapted to engage notches 9^a in the lower end of the cover nipple 15, and the 5 pin 8^b is adapted to engage notches 9^b in the upper face of the rib 16.

Each series of notches 9^a and 9^b is four in number, and the pins 8^a and 8^b are held in engagement with the notches by the spring 10 17 which also, acting downwardly, holds the lugs 20 in the notches 21 and such lugs may be released from the notches by relieving pressure on the springs through cap 9. However, when the feed stem or needle 15 valve is turned forcibly the pins will roll out of the notches pressing the spring 17, and the pins will engage other sets of notches.

Thus the valve or stem is held from accidental displacement. The locking pins may move vertically with respect to the valve stem or needle valve, since they move in the slot 7^a.

In Figs. 5 to 9 there is shown a construction 25 wherein the cup 21 is similar to the cup 1 of Fig. 1, having the arc shaped openings 22 in its top for permitting the insertion of lubricant, and at each side of the central opening for the valve 23 there is 30 provided the recesses 24 corresponding to the recesses 19 of Figs. 1 to 4. These recesses are adapted to be engaged by balls 25 held in the cover 26, which is similar to the cover 11, having similar radial extensions for closing the openings 22. A lug 27 is secured to the under face of one of the extensions at the center thereof, and this lug is adapted to engage a notch 28 in the 35 upper edge of the body of the cup at the center of one of the openings 22.

The cup shaped top 28 of the valve corresponds to the cup shaped extension, or squared on both sides, and is in the present instance, not rigid with the valve, but is 45 mounted to slide thereon up and down. The valve stem has a head 29 which is provided with oppositely extending ears 30, and these ears 30 extend below the head 29 as well as above, and provide means for engaging radial notches 31 in the cup shaped member 28. With this arrangement, the valve stem is locked against displacement, the spring (not shown) corresponding to the 50 spring 17 holding the cup shaped member 28 in engagement with the ears 30 as well as holding the cover 26 in locked position on the cup.

In either construction, the top or cover of 60 the oil cup is held from accidental displacement by the balls and the recesses, as well as by the lugs and the notches. In the construction of Figs. 5 to 9, the valve stem is also locked against accidental release, it being necessary to depress the cup shaped member 28 before the valve stem can be

turned. The depression, however, may be brought about by the turning of the stem, additional force being necessary to overcome the resistance of the spring.

I claim:

1. An oil cup having in the top thereof oppositely arranged openings for permitting the insertion of lubricant, and a cover mounted to rotate in the cup and having radial extensions fitting over the openings 75 for closing the same, and releasable locking means between the cup and the cover released by forcible turning of the cover, a valve in connection with the cup for controlling the flow therefrom, said valve passing through the top of the cup and through the cover, a cup shaped member in connection with the outer end of the valve, a spring arranged between the said cup shaped member and the cover and normally pressing the 80 cover to its seat, the valve having a head engaging outside of the cup shaped member, and releasable locking mechanism between the member and the head.

2. An oil cup having in the top thereof 90 oppositely arranged openings for permitting the insertion of lubricant, and a cover mounted to rotate on the cup and having radial extensions fitting over the openings 95 for closing the same, and releasable locking means between the cup and the cover released by forcible turning of the cover, a valve in connection with the cup for controlling the flow therefrom, said valve passing through the top of the cup and through the cover, a cup shaped member in connection with the outer end of the valve, and a spring arranged 100 between the said cup shaped member and the cover and normally pressing the cover to its seat.

3. An oil cup having in the bottom thereof a port, and a needle valve coöperating with the port, said valve being slotted longitudinally, two locking pins arranged transversely of the slot and extending beyond the 110 valve at each end, the cup having in the cover thereof notches arranged both top and bottom about the stem for engagement by the ends of the pins, and a spring pressing said pins toward the notches, the upper end of the valve outside of the cup having 115 a cup shaped extension, and the spring being arranged within the extension and bearing against the extension at its upper end, the top of the cup having a box co-axial with 120 the stem in which the lower end of the spring is seated, and the notches being inside the box and on bottom of cover nipple.

4. An oil cup having in the bottom thereof a port, and a needle valve coöperating with the port, said valve being slotted longitudinally, two locking pins arranged transversely of the slot and extending beyond the valve 125 at each end, the cup having in the cover thereof notches arranged about the stem for 130

engagement by the ends of the pins, and a spring pressing said pins toward the notches, the upper end of the valve outside of the cup having a cup shaped extension, and the 5 spring being arranged within the extension and bearing against the extension at its upper end.

5. An oil cup having in the bottom thereof a port, and a needle valve coöperating with

the port, said valve being slotted longitudinally, two locking pins arranged transversely of the slot and extending beyond the valve at each end, the cup having in cover thereof notches arranged about the stem for engagement by the ends of the pins, and a spring 15 pressing said pins toward the notches.

WILLIAM HENRY LINDENFIELD.
